UNITED STATES PATENT OFFICE.

HAROLD S. WHITE, OF PHILADELPHIA, PENNSYLVANIA, ASSIGNOR TO OWL CIGAR LIGHTER CO., OF PHILADELPHIA, PENNSYLVANIA, A CORPORATION OF PENNSYLVANIA.

DESIGN FOR A CIGAR-LIGHTER.

56,545.

Specification for Design.

Patented Nov. 2, 1920.

Application filed May 3, 1920. Serial No. 378,699. Term of patent 14 years.

To all whom it may concern:

Be it known that I, HAROLD S. WHITE, a citizen of the United States, residing at Philadelphia, in the county of Philadelphia and State of Pennsylvania, have invented a new, original, and ornamental Design for Cigar-Lighters, of which the following is a specification, reference being had to the accompanying drawing, forming part thereof.

The figure is a plan view of a cigar lighter, showing my new design, the salient features of which are a pedestal and supporting base upon which stands the representation of a group of three owls from the center of which group projects upward a cigar lighter.

I claim:

The ornamental design for a cigar lighter as shown.

HAROLD S. WHITE.
